(57) **CLAIM**

The ornamental design for an apparatus holder support device, as shown and described.

DESCRIPTION

FIG. 1 is a perspective view of an apparatus holder support device;

FIG. 2 is a front side view of the apparatus holder support device shown in FIG. 1,

FIG. 3 is a bottom view of the apparatus holder support device shown in FIG. 2,

FIG. 4 is a left end view of the apparatus holder support device shown in FIG. 2,

FIG. 5 is a right end view of the apparatus holder support device shown in FIG. 2,

FIG. 6 is a rear side view of the apparatus holder support device shown in FIG. 2; and,

FIG. 7 is a top view of the apparatus holder support device shown in FIG. 2.

The apparatus holder support device is used for supporting an apparatus support device specifically adapted to cradling a particular apparatus such as a wireless phone, GPS, a PDA device, a telephone or other equipment in a convenient position on a smooth surface such as a windshield of a motor vehicle.
